UNITED STATES PATENT OFFICE.

JOHN SIARKOWSKI, OF BUFFALO, NEW YORK.

MACHINE FOR CUTTING BUTTONHOLES.

Application filed July 12, 1926. Serial No. 121,912.

This invention relates to improvements in machines for cutting button-holes in garments.

One of its objects is the provision of a 5 foot-operated machine of this character which is reliable and efficient in operation, which produces uniform work, and which affords a material saving of time and labor over machines now in use.

10 Another object of the invention is to provide a simple, compact and inexpensive button-hole machine which has been designed for ready attachment to a table or other support, and whose parts are so organized 15 and arranged that it is easy and convenient to operate.

A still further object is to provide the machine with means for facilitating the spacing of the button-holes in the garment 20 preparatory to cutting them.

In the accompanying drawings: Figure 1 is a side elevation of a button-hole machine embodying my invention. Figure 2 is a top plan view thereof. Figure 3 is a transverse 25 vertical section on line 3—3, Fig. 1. Figure 4 is an enlarged transverse section on line 4—4, Fig. 2. Figure 5 is a fragmentary vertical longitudinal section on line 5—5, Fig. 4. Figure 6 is a fragmentary sectional 30 side view of a modification of the invention.

Similar characters of reference indicate corresponding parts throughout the several views.

In the preferred embodiment of the invention illustrated in the drawings, the improved machine is designed for attachment 35 to a table 10 or other appropriate support, and for this purpose its main frame 11, which carries the various working parts of 40 the machine, is shaped to embrace the front edge of the table, as shown in Fig. 1, a clamping screw 12 mounted in the lower arm 13 of the frame serving to reliably hold 45 the machine in place. The upper arm 14 of this frame rests on the top of the table and terminates at its rear end in garment-supporting members or ledges 15 which are 50 spaced apart laterally to form a longitudinal slot or opening 16 between them for receiving an adjustable width-gage 17 rotatably mounted on a horizontal pin 18 projecting from the arm and centrally of said opening, as shown in Figs. 4 and 5. This widthgage is polygonal in cross section and 55 its flat faces 19 are of varying lengths to produce different-sized button-holes in the

garments. The front end of the width-gage normally bears against the opposing rear wall of the arm 14 and is provided with an annular row of depressions 20, one or another of which is adapted to engage a tooth 21 in such rear wall. A nut 22 is applied to the threaded end of the pin 18 for preventing displacement of the width-gage. As shown in Fig. 4, the width of the opening 60 16 at its top is sufficient to expose but one of the faces 19 of the width-gage, such face being flush with the corresponding upper sides of the ledges 15 to permit the garment 65 to rest smoothly thereon during the cutting-operations.

Mounted on the frame 11 for vertical movement toward and from the width gage 17 is a cutter-head 23 of substantially L-shape, the upright member 24 thereof being 70 guided in a vertical slot 25 formed in the front portion of the frame and the horizontal arm or member 26 thereof overhanging the upper frame-arm 14. A knife 27 and punch 28 are removably mounted in the cutter head arm 26 and positioned directly over the width gage, as shown in Figs. 1 and 5. The knife may be seated in a groove 29 in the underside of said arm and held therein by screws 30 while the punch is seated in an 75 opening 31 and is of tubular form to permit the discharge of the waste material 80 therethrough. Springs 32 applied to the cutter-head serve to normally hold it in its elevated, inoperative position shown by dotted 85 lines in Fig. 1. In this position, a stop-flange 33 on the lower end of the upright member 24 of the cutter-head engages the 90 opposing lower end of the frame 11.

The cutter-head is preferably lowered to 95 its operative position, shown by full lines in Fig. 1, by means of a foot-lever 34 fulcrumed at 35 and connected by a link 36 with an ear 37 formed at the lower end of the cutter-head member 24. A spring 38 applied to this lever tends constantly to swing the lever upwardly to its inoperative position.

It will be understood that when cutting a 105 buttonhole in the garment, a fragment of which is shown at 39, the same is placed over the supporting ledges 15 and the width gage 17 in the manner shown in Fig. 4. For the purpose of reliably holding the garment 110 in position on the ledges and preventing accidental shifting or displacement thereof during the cutting operation, the cutter-

head is provided on either side of the knife 27 with clamping feet or pads 40, 40. These pads are adapted to bear flatwise on the garment and have plungers 41 rising therefrom which are guided for vertical movement in socketed brackets 42 attached by screws 43 to the opposite sides of the cutter-head arm 26. Springs 44 arranged in the sockets of these brackets and bearing on the tops of the plungers yieldingly resist upward displacement of the pads, while companion pins 45 and slots 46 limit their movement in either direction. The front ends of the pads are curved upwardly to easily facilitate the insertion of the garment between them and the supporting ledges.

To properly determine the location of the buttonhole from the edge of the garment, an adjustable gage bar 47 is arranged transversely of the frame 11 and forwardly of the width gage 17. This edge-gage is preferably carried by a pair of supporting arms 48 disposed on opposite sides of the frame and mounted on the ends of a bolt 49 guided for longitudinal movement toward and from the width gage and knife 27 in slots 50. Along its upper edge the frame has a suitable scale 51 along which the edge-gage is adapted to traverse and the latter is held in a desired set position by the nut 52 or similar clamping device applied to the bolt 49.

Disposed beneath the width-gage and extending transversely of the machine is a measuring device 53 against which the garment is adapted to be placed for marking and spacing the button-holes preparatory to cutting them. The frame 11 is provided beneath the width gage with a horizontal recess 54 for removably receiving the measuring device, the latter being provided in its underside with grooves 55 engaging corresponding tongues 56 in the bottom wall of the recess. Applied to the upper side of the measuring device are a pair of bowed springs 57 which engage grooves 58 in the undersides of the frame-ledges 15. By this construction and arrangement of parts, the measuring device is conveniently located, it does not interfere with the other parts of the machine and it is reliably held against displacement both lengthwise and crosswise of the machine.

Briefly stated, the operation of the machine is as follows:

Assume the width-gage 17 and edge-gage 47 to be properly set for the length of button-holes desired and for the location thereof from the edge of the garment, respectively. The garment is first placed against the measuring device or rule 53 and the tailor marks the location of the button-holes according to the spacing desired. He then places it over the width gage and ledges 15 in the manner shown in Figs. 1 and 2 with the edge of the garment abutting

against the edge-gage and a given mark for the button-hole in line with or directly over the operating face 19 of said width-gage. The foot-lever 34 is now depressed from the dotted line to the full line position shown in Fig. 1, which operation cuts the button-hole in the garment. After releasing the foot-lever, the garment is shifted transversely of the machine to cut the next button-hole and so on.

This improved machine is manifestly simple and compact in construction, requiring but a minimum amount of space in the tailor's shop; its operation is easy and leaves the hands of the operator free to handle the garment; and it permits the uniform cutting of a maximum number of button-holes in a minimum period of time.

In the modification shown in Fig. 6, the washer 59 which is arranged between the end of the width-gage 17 and its clamping nut 22, is provided with a depending lip or brace 60 resting at its lower end on the projecting rear end 14^a of the frame-arm 14, as shown, or on the measuring device 53, as shown by dotted lines in Fig. 5. This lip functions as a brace and supports the free end of the width-gage when pressure is exerted thereon and eliminates the strain on the pin 18.

I claim as my invention:

1. A button-hole cutting machine, comprising a frame having an upright guideway and an arm terminating at its free end in a pair of spaced supports on which the garment is adapted to be placed, a width-gage disposed in the space between said supports, a vertically-slidable cutter-head having a part engaging said frame-guideway and a part overhanging said width-gage, a knife applied to the last-named cutter-head part and arranged to cooperate with the width-gage to form a button-hole in the garment, and means for actuating said cutter-head into and out of its operative position.

2. A button-hole cutting machine, comprising a pair of relatively movable members, one of said members constituting a support for the garment and the other a cutter-head, a width-gage mounted on said supporting member, a knife applied to said cutter-head and arranged to cooperate with the width-gage, and means applied to said cutter-head for holding the garment on to said supporting member.

3. A button-hole cutting machine, comprising a pair of relatively movable members, one of said members constituting a support for the garment and the other a cutter-head, a width-gage mounted on said supporting member, a knife applied to said cutter-head and arranged to cooperate with the width-gage, and garment-engaging elements carried by said cutter-head and disposed on opposite sides of its knife, said elements being movable with said cutter-head toward

and from the work and adapted to hold the garment on to said supporting member in the operative position of the cutter-head.

4. A button-hole cutting machine, comprising a pair of relatively movable members, one of said members constituting a support for the garment and the other a cutter-head, a width-gage mounted on said supporting member, a knife applied to said cutter-head and arranged to cooperate with the width-gage, brackets arranged on opposite sides of the cutter-head adjacent its knife, and garment-engaging elements yieldably suspended from said brackets.
5. A button-hole cutting machine, comprising a pair of relatively movable members, one of said members constituting a support for the garment and the other a cutter-head, a width-gage mounted on said supporting member, a knife applied to said cutter-head and arranged to cooperate with the width-gage, brackets arranged on opposite sides of the cutter-head adjacent its knife, garment-engaging elements including plung-

ers slidable vertically in said brackets, and springs for urging said elements into clamping engagement with the garment.

6. A button-hole cutting machine, comprising a frame having an upright guideway and an arm terminating at its free end in a pair of spaced supports on which the garment is adapted to be placed, a width-gage disposed in the space between said supports, an adjustable edge-gage for the garment arranged transversely of said frame-arm and forwardly of said width-gage, means for holding the edge-gage in a set position, a vertically-slidable cutter-head having a part engaging said frame-guideway and a part overhanging the width-gage and the edge-gage, a knife applied to the last-named cutter-head part and arranged to cooperate with the width-gage to form a button-hole in the garment, and means for actuating said cutter into and out of its operative position.

JOHN SIARKOWSKI.
